UNITED STATES PATENT OFFICE.

HARRY BUXTON HARTMAN, OF SCOTTDALE, PENNSYLVANIA.

SAFETY RAZOR.

Application filed May 3, 1922. Serial No. 558,165.

To all whom it may concern:

Be it known that I, HARRY B. HARTMAN, citizen of the United States, residing at Scottsdale, in the county of Westmoreland and State of Pennsylvania, have invented certain new and useful Improvements in Safety Razors, of which the following is a specification.

This invention relates to an improvement in safety razors.

A primary object of the invention is to provide a simple, practical and reliable construction that may be easily and economically manufactured, and which may be readily manipulated to quickly clamp the blade in position or release the same and yet at the same time hold it securely in place when in use. In that connection the means for clamping or holding the blade also constitutes a guard or protector for the corners of the blade thereby reducing the danger of cutting or scratching by the corner of the blade.

A further object of the invention is to provide a novel universal joint for connecting the blade carrier with the handle. In that connection it is proposed to provide a spring tensioned joint whereby the blade carrier may be readily set to the desired adjusted position and frictionally held in position without requiring other attention.

A still further object is to provide a universal joint connection that is susceptible of being easily manufactured and assembled at a minimum of expense and labor.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:

Figure 1 is a plan view of a complete razor embodying the present improvements and without the blade.

Figure 2 is a plan view of the blade carrier showing a blade positioned therein.

Figure 3 is a horizontal sectional view taken on the line 3-3 of Figure 2.

Figure 4 is a detail sectional view taken on the line 4-4 of Figure 2.

Figure 5 is a detail perspective view of the blade.

Figure 6 is a side elevation of the razor partly in section showing more clearly the universal joint connection.

Figure 7 includes side and top views of the 60 socket portion of the joint.

Figure 8 is a detail view of a straight form of handle.

Figure 9 is a side elevation illustrating the 65 use of the handle in Figure 8.

Similar reference characters designate corresponding parts throughout the several figures of the drawings.

In the embodiment of the invention shown in the accompanying drawings it is proposed to provide a blade carrier 1 mounted upon a handle H by a novel universal joint J whereby the blade and handle may be adjusted to any desired and convenient angle to suit the individual user, as will herein-after more fully appear.

Referring first to the blade carrier 1 it will be observed that the front edge is formed with a plain guard portion 2 while the body is preferably provided with a pair 80 of upstanding posts or lugs 3-3 for entering the openings 4-4 of a blade B thereby to properly position and hold the cutting edge of the blade with reference to the guard edge 2.

For the purpose of securing or locking the blade to the carrier novel swinging clips designated generally as 5 are used. As will be seen from the drawings each clip is pivoted as indicated at 6 adjacent a rear corner 90 of the carrier so that the same may be moved into and out of overlapping or embracing relation with the blade and carrier to clamp the blade in place. Structurally each clip 5 preferably consists of a body 7 the rear end 95 of which is pivoted to the underside of the carrier while the forward end is made of substantially U-shaped cross section thereby providing upper and lower clamping jaws 8 and 9 respectively for overlying and engaging with the blade and underlying and engaging with the bottom edge of the carrier.

In connection with the upper clamping jaw 8 it will be observed that the same is provided with a raised portion 8^a for fitting 100 over and clearing the upstanding posts or lugs 3 which project through the openings in the blade B.

Also another important and distinctive feature of the jaw 8 is that it extends forwardly as indicated at 10 to overlie or cover the corner of the blade B thereby provid-

ing a guard for eliminating the possibility of cutting or scratching by the corner of the blade which would be otherwise left unprotected.

5 From the foregoing it will be apparent that the present invention provides a carrier for holding a single edged blade B having perforations for fitting over fixed posts or lugs 3 on the carrier, the blade being then prevented from being displaced from the posts by means of the pivoted or swinging clips 5 operating in the plane of the carrier. In that connection it will be observed that the interlock between the 10 blade and the lugs reliably holds the blade in position so that the cutting edge thereof will always be properly positioned with reference to the guard. Then, after the 15 clips have clamped the blade to the carrier 20 the blade will be effectually held against displacement from the lugs while at the same time the guard edges of the clips will conceal and protect the corners of the blade so that they will not cut or scratch the face 25 during shaving.

Referring now to the universal joint connection J for adjustably mounting the blade carrier on the handle it will be observed that the same includes ball and socket members which are capable of facile assembly and also are of great simplicity, thereby materially enhancing production in quantities. To that end the present arrangement includes a socket member or shell 11 30 which is preferably in the form of a tube having at one edge the bosses 12 for fitting into openings 13 in the blade carrier 1 so that the same may be riveted to the blade carrier thereby to hold the socket member 35 firmly in place.

The end of the member 11 opposite that having the bosses is slotted as indicated at 40 14 to provide the socket seats 15 which when bent inwardly as shown in the drawing provide a seat for receiving the ball 16. When the seats are bent into position to provide the base of the socket for receiving the ball a four-way slot is provided, and as shown 45 in Figure 9 for example, the shank 17 of the handle may fit into any one of the wings of the four-way slot to thereby establish an interlock between the handle and the socket member if desired. However, it is 50 one of the objects of the present invention 55 to provide a ball and socket joint which becomes automatically held in adjusted or set position and therefore a spring 18 is utilized to frictionally hold the ball 16 against the seats 15 of the tubular member 11. This spring 18 is confined between the ball and the underside of the blade carrier 1 so that when the parts are assembled 60 the spring is concealed within the housing afforded by the tubular member 11 and by 65 reason of the compression thereof due to its

confinement in the relative small space between the ball and the blade carrier the ball is pressed against the seats 15 with sufficient friction to hold the blade carrier at any desired angle with reference to the 70 handle.

As will be observed from the drawing the shank 17 of the handle H is fitted with a spindle portion 17^a for receiving the ball 16. After the ball is placed over the spindle 75 the end of the latter may be riveted to securely hold the ball thereto. Also, it will be apparent that the shank 17 of the handle H may be curved or angular as shown in Figure 6 or may be straight as 80 shown in Figures 8 and 9.

With reference to the manner of assembling the construction described it may be observed that the ball 16 may be dropped into the spring housing or socket member 85 11 and the spindle portion 17^a of the handle shank placed through the opening in the ball and the end of the spindle riveted while the ball is in the housing. The spring 18 may then be placed behind the ball 16 90 and the bosses 12 inserted in the openings 13 in the blade carrier. The ends of the bosses 12 may then be riveted to hold the spring housing firmly to the carrier and also confine and house the spring to cause the 95 same to exert the proper tension on the ball.

When the parts are assembled the razor blade holder can be revolved a complete turn and when it is desired to lock it at a shaving angle the shank 17 may be placed 100 into one of the slots 14.

Without further description it is thought that the features and advantages of the present improvement will be readily apparent to those skilled in the art and it will 105 of course be understood that changes in the form, proportion and minor details of construction may be resorted to without departing from the spirit of the invention or scope of the appended claims. 110

I claim:—

1. A safety razor including a blade carrier having means for interlocking with the blade to position the same with reference to the guard edge thereof, clips pivoted to 115 the rear corners of the carrier and having clamping jaws for embracing the edges of the blade and carrier, one of the said clamping jaws of the clips having a guard portion extending forwardly and overlying the 120 corner of the blade.

2. A safety razor including a blade carrier, upstanding projections thereon, a blade provided with openings for fitting over said projections, and combined blade clamping 125 and guard clips pivotally secured to the carrier.

3. A safety razor including a blade carrier having upstanding posts thereon, a blade provided with openings for receiving 130

said posts, and pivoted blade clamping clips arranged at the opposite side edges of the blade carrier and consisting of a body pivotally connected to the carrier at one end 5 while the opposite end is of substantially U-shaped formation providing clamping jaws, one of said clamping jaws being provided with a recess for receiving the portions of the upstanding projections protruding through the blade and also provided 10 with an extension for overlying and guarding the corner of the blade.

4. A safety razor including a blade carrier, and combined blade clamping and 15 guard clips pivotally secured to the carrier and adapted to project beyond the position of the corner of the blade when moved into clamping position with the blade.

5. A safety razor including a blade carrier, a tubular socket member fitted thereto, 20 said socket member having a slotted ball seat at one end and connected at the other end with the carrier, and a handle having an angular end portion, a ball carried by 25 the tip of the angular end portion of the handle and adapted to rest in said ball seat,

and a spring confined between the ball and the carrier.

6. A safety razor including a blade carrier, a tubular socket member rigidly secured at one end to the under side of the blade carrier, and the opposite end thereof being provided with a slotted ball seat, a ball having a bearing on said seat, a spring confined between the carrier and the ball 30 for frictionally holding the latter to its seat, and a handle fitted to the ball and adapted to register with said slots to temporarily lock the blade carrier in a set angular position to provide the desired shaving angle for the blade on the blade carrier. 40

7. A safety razor including a blade carrier, and combined blade clamping and guard clips shiftably secured to the carrier and adapted to mask the corner of the blade 45 when moved into clamping relation thereto.

In testimony whereof I hereunto affix my signature in the presence of two witnesses.
